TOILET SEAT CLOSER

George Washington Cashwell, Elizabethtown,
N. C.

Application October 7, 1940, Serial No. 360,196

2 Claims. (Cl. 4—251)

This invention relates to outdoor toilets and more particularly to a means for automatically closing the cover for the seat.

An object of this invention is to provide in an outdoor toilet, a hinged seat and means connected to the door by which the seat is automatically closed upon opening of the door.

Another object of this invention is to provide in a device of this type, a means whereby the swinging of the cover to a closed position is cushioned so that the cover will lightly drop to a closed position.

A further object of this invention is to provide a device of this kind which can be used for closing a plurality of seat covers at one operation.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing—

Figure 1 is a vertical section taken on line 1—1 of Figure 2 of an outdoor toilet having a device constructed according to an embodiment of this invention mounted on the seat and connected to the seat cover.

Figure 2 is a fragmentary sectional view taken on the line 2—2 of Figure 1.

Figure 3 is a fragmentary sectional view taken on the line 3—3 of Figure 1.

Figure 4 is a longitudinal section taken through one of the seat cover cushioning means.

Referring to the drawing, the numeral 10 designates generally a housing including a front wall 11, a rear wall 12, a roof 13 and a floor 14. A door 15 is hingedly secured to the front wall 11 by hinges 16 and a toilet seat 17 is disposed interiorly of the housing 10, being secured at its 45 rear edge to the rear wall 12 and secured to an upright 18 which extends upwardly from the bottom wall 14.

A seat 17 in the present instance is provided with a pair of spaced apart openings 19 and 20 and a pair of seat covers 21 and 22 are hingedly secured to a strip 23 which is fixed to the upper surface of the seat 17 rearwardly of the openings 19 and 20. In order to provide a means whereby the seat covers 21 and 22 may be automatically 55 swung to a closed position, which is the position

shown in dotted lines in Figure 1, I have provided a seat cover closing lever 24 which is pivotally mounted on a pivot 25 secured to a rafter 26 forming part of the roof supporting means for supporting the roof 13.

The lever or arm 24 at its lower end is provided with a pair of cover engaging arms which in front elevation are of substantially L-shape and include a horizontally disposed arm 27 provided at one end thereof with a rearwardly disposed 10 extension 28 through which a fastening device 29 engages in order to secure the extension 28 to the lower end portion of the lever or arm 24. The arm 27 at its opposite or outer end is formed with a substantially S-shaped extension 30 as 15 shown in Figure 1, which has a free end 31 of arcuate configuration which is directed forwardly and which is adapted to contact with the seat cover 21 at a point slightly below the upper end of the cover 21 when this cover is in a raised 20 position.

A second seat cover lowering member generally designated as 32 is secured to the opposite side of the lever 24 and is of a configuration similar to the cover closing means designated 27, 28, 39 25 and 31. The cover closing member 32 is adapted to engage the cover 22 and extends oppositely from the cover closing means for the cover 21. A second rock lever 33 is pivotally mounted on a pivot 34, which is carried by the rafter 26 forwardly of the pivot 25 and a link 35 is pivotally connected at one end as at 36 to the lever 24 adjacent the upper end of this lever and is also connected by means of a pivot 37 to the lever 33 at a point upwardly from the lower end of 30 this latter lever.

A link 38 is connected at one end to an eye or fastening member 39 which engages the lower portion of the forward rock lever 33 and the opposite end of the link 38 is connected to an eye or fastening member 40 which is fixed to the door 15 at a point closely adjacent the hinge 16. A door closing spring 41 is connected at one end to an eye or fastening member 42 which is fixed to the rafter 26 and the opposite end of the spring 41 is connected to an eye or fastening member 43 which is fixed to the door 40. The spring 41 is adapted to constantly urge the door 15 to a closed position.

In order to provide a means whereby the seat covers 21 and 22 may be cushioned in their downward swinging movement, I have provided a pair of dash-pots generally designated as 44 and 45 which are disposed inwardly from the confront- 50 55

ing edges of the two covers 21 and 22. These dash-pots or cushioning members 44 and 45 are of like construction and as shown in Figure 4 include a cylinder 46 having heads 47 and 48 at 5 the opposite ends of the cylinder 46 and a piston 49 is slidable in the cylinder 46.

A piston rod 50 is secured at one end to the piston 49 and is slidable through the head 48. The piston 49 may be formed with an opening 10 51 therethrough which is adapted to gradually release air or other fluid so that the movement of the piston 49 will be cushioned. The extended end of the piston rod 50 is formed with an opening 52 through which an eye 53 carried by a 15 piston operating link 54 engages. The lower end of the link 54 is secured as at 55 to one edge of the seat 21. The cushioning member 45 is of similar construction to the cushioning member 44 and includes a piston rod 56 which is connected by a link 57 to the seat 22 as by a pivotal 20 means 58.

In the use and operation of this device, the seat cover 21 is raised during the use of the seat 17 and in its raised position, the seat 21 will rest 25 against the seat lowering member 32. In this position, the cover 21 is inclined rearwardly from the vertical and when the door 15 is open with the cover 21 in a raised position, the swinging of the door 15 on the hinge means 16 will pull the forward lever 33 forwardly and the rear lever 24 will also be pulled forwardly by means of the connecting link 35. Forward swinging of the lower end of the lever 24 will cause the cover 21 to be pushed forwardly off center and the cover 30 21 will then gravitantly swing downwardly to a closed position, which is the dotted line position shown in Figure 1. After the cover 21 is swung forwardly by the lever 24 and the closing member 31, the further downward swinging of 35 the cover 21 by gravity will be cushioned by means of the dash-pot 44. This dash-pot will permit the cover 21 to gradually swing downwardly to a closed position and will eliminate the slam or sudden swinging downwardly of the cover 21, as would be the case if the dash-pot 44 were eliminated.

What I claim is:

1. In a toilet including a housing having a roof, front, rear and side walls, a floor and a door opening in its front, a door hinged to said front wall for closing said opening, a toilet seat in the housing supported above said floor and a cover for and hinged to said seat; a vertically disposed cover closing lever swingingly suspended at its upper end from said roof and having laterally extending means at its lower end engageable with the back of the cover when the latter is raised for swinging the cover downwardly to closed position, a second lever swingingly suspended at its upper end from said roof forwardly of said first lever, a link pivotally connected to said levers intermediate the ends of the latter, a second link pivotally connected to said door and to the lower end of said second lever whereby to rock said second lever forwardly upon opening of the door whereby the first lever is moved in a like direction for closing said seat, and a spring connected to the door and to the roof for normally urging said door to said closed position and for holding said first lever in an inoperative position. 5 10 15 20 25

2. In a toilet, a housing having a door opening, a hinged door for closing said opening, a toilet seat within the housing, a cover for and hinged to said seat, a vertically disposed cover closing lever swingingly suspended at its upper end disposed over the seat and having its lower end provided with means engageable with the back of the cover, when the latter is raised for swinging the cover downwardly to closed position on the operation of said lever, a vertically disposed second lever swingingly suspended at its upper end and disposed forwardly of said first lever, a link between and pivotally connected to said levers intermediate their ends, a second link disposed below the first link pivotally connected to said door and to said second lever whereby to rock the latter forwardly upon the opening of the door to thereby operate the first lever for closing said seat, and a spring connected to the door and to the housing for normally urging said door to closed position and for holding said first lever in an inoperative position. 30 35 40 45 50

GEORGE WASHINGTON CASHWELL.
